UNITED STATES PATENT OFFICE.

STANLEY KASPER, OF BUXTON, IOWA.

CONVERTIBLE LADDER AND BENCH.

1,287,861.

Specification of Letters Patent. Patented Apr. 20, 1920.

Application filed July 2, 1919. Serial No. 308,248.

To all whom it may concern:

Be it known that I, STANLEY KASPER, a citizen of Russia, residing at Buxton, county of Monroe, and State of Iowa, have invented 5 certain new and useful Improvements in Convertible Ladders and Benches, of which the following is a specification.

This invention has as its principal object to provide a structure which may be used 10 when in an expanded condition as a ladder, and which is capable of being contracted and disposed horizontally so as to be used as a bench.

A further object is to provide a convert- 15 ible ladder with elements which may be ex- tended, forming legs or supports, while the rungs of the ladder are hinged so as to form divisions when the device is used as a seat or bench.

20 These and other like objects are attained by the novel construction and combination of parts hereinafter described, and shown in the accompanying drawings, forming a material part of this disclosure, and in which—

25 Figure 1 is a perspective view showing the device in a folded position, when used as a bench.

Fig. 2 is a front elevational view showing the parts extended as a ladder, and

30 Fig. 3 is a transverse sectional view drawn to an enlarged scale, the section being taken on line 3—3 of Fig. 2.

Referring to the drawings in detail, a pair 35 of rectangular bars 10 and 10' are engaged by hinges 11 with strips 12 and 12' acting as legs, the strips 12 being secured at the extreme end of the bars while the strips 12' engage said bars at a distance from the ends so that when folded they lie in the same 40 plane.

The lower ends of the strips 12 and 12' contain openings 13, engageable with pins 14, extending down from the lower surface of the bars 10 and 10' so as to hold the bars 45 spaced parallel apart when the device is being used as a ladder, while the strips obviously may be turned outward, in planes at right angles to the bars, when the device is used as a bench.

50 Pivoted upon screws 15, upon the upper surface of the bar 10' are swinging plate elements 16 containing recesses 17 upon their inner edges, near their outer ends, the same being engageable with pins 18, set in 55 the opposite bar 10 when the bars are folded as shown in Fig. 1, the recesses also engag-

ing with pins 19 set in the bars 10' so that the strips 16 may be in longitudinal relation with the bar 10' when the device is used as a ladder, thus holding the bars in 60 spaced relation in either of their positions.

Engaged upon the inner adjacent edges of the bars 10 and 10' are hinges 20 and 21 the 65 hinges being alike but secured in opposite relation upon the bars, and joined by the hinges 22, connected at their centers by other hinges 23 and 24 also arranged in opposite relation, so that the bars 22 are capable of folding, presenting 70 V-shaped structures when in a partially folded condition, which serve as partitions along the bench forming individual seats upon the upper surfaces of the bars 10 and 10'. The bars are held in fixed relation by the cross strips 16 at the ends of the structure, and when the bars 10 and 10' are 75 spread, the strips 22 act as the rungs of the ladder.

If it be preferred the pins 17 and 19 may be formed with disks 25, slidably received 80 in recesses 26 and thrust forward by coiled compression springs 27, held in the recesses by the plates 28, secured to the opposite sides of the bars by rivets 29, this construction being best shown in Fig. 3. 85

From the foregoing it will be seen that an effective and practical device has been presented, which may be used either as a ladder or as a bench providing seats for a number of persons. 90

I claim—

1. In a convertible ladder and bench, the combination with a pair of rectangular bars, means hinged to one of said bars engageable with the opposite disposed bar whereby the 95 bars are held in rigid spaced relation, and a plurality of sectional rung elements hingedly engaged between the inner edges of said bars, the sections of each rung being hingedly attached so as to be capable of 100 folding alternately above and below the surface of said bars when the device is used as a seat.

2. In a convertible ladder and bench, the combination with a pair of rectangular bars, 105 strips hingedly engaged at the ends of said bars, said strips having openings at their free ends, and pins in the opposite bars engageable with the mentioned openings, of other strips pivoted upon the opposite sides 110 of said bars at the ends thereof, pins set in said bars engageable with slots formed in

the free ends of said pivoted strips, and a plurality of sectional transverse bars hingedly engaged between the first mentioned bars, said transverse bars being hinged to extend alternately above and below the surfaces of the first mentioned bars when said bars are in a relatively closed position.

3. In a combined ladder and bench, the combination with a pair of bars, support elements hingedly engaged in the ends of said bars, means for holding said support elements engaged with said bars when in a raised position, swinging clips pivotally engaged with one of said bars, said clips hav-

ing slots in their opposite ends, pins set in the opposite bar engageable with said slots, means permitting the depression of said pins for allowing a displacement of said clips, other pins set in the bar on which said clips are pivoted whereby said clips are held extended parallel to said bars, and a plurality of hingedly engaged sectional rungs extended between the inner edges of said bars, said rungs being adapted to fold alternately in opposite directions.

In testimony whereof I have affixed my signature.

STANLEY KASPER.
